[57] CLAIM

The ornamental design for a bird feeder, as shown.

DESCRIPTION

FIG. 1 is a perspective view taken from the front, top and one side of a bird feeder showing my new design;
FIG. 2 is a perspective view taken from the rear, and opposite side thereof;
FIG. 3 is a side elevational view thereof, the opposite side being a mirror image of the side shown;
FIG. 4 is a front elevational view thereof, the rear being a mirror image except for the aperture in the roof; and,
FIG. 5 is a top plan view thereof.
